CLEANING BLOCK

Application filed September 26, 1930. Serial No. 484,635.

This invention relates to new and useful improvements in cleaning blocks or devices especially adapted for removing dirt and foreign matter from surfaces and has for the primary object the provision of cleaning elements of different textures or abrasives, whereby the device may be employed for scouring surfaces requiring different abrasives in order to remove the foreign matter without injury to the finish thereof.

Another object of this invention is the provision of a scraping element carried by the cleaning element, whereby coarse or hard foreign matter may be loosened from a surface prior to scouring the surface with the cleaning element.

A further object of this invention is the provision of a scouring block of the above stated character which will be simple, durable and efficient, and which may be manufactured and sold at a comparatively low cost.

With these and other objects in view as will become more apparent as the description proceeds, the invention consists in certain novel features of construction, combination and arrangement of parts as will be herein-after more fully described and claimed.

For a complete understanding of our invention, reference is to be had to the following description and accompanying drawings, in which:

Figure 1 is a perspective view illustrating a cleaning block constructed in accordance with our invention.

Figure 2 is a plan view with one of the cleaning elements removed illustrating the application of the scraping element to the other cleaning elements.

Figure 3 is a sectional view illustrating the scraping element embedded between the cleaning elements.

Referring in detail to the drawings, the numeral 1 indicates a cleaning block in entirety and includes cleaning elements 2 and 3 constructed from rubber impregnated with abrasive material of any desired character and the element 3 is preferably of a substantially hard rubber, while the element 2 is made from spongy rubber as shown in Figure

3 for the purpose of cleaning surfaces of different textures, as for instance, the element 3 may be employed for scouring cooking utensils and the like while the element 2 may be employed for scouring bath room fixtures, 55 tiling and the like and preferably the element 3 is suitably colored for the purpose of permitting a person to distinguish the difference between the cleaning elements 2 and 3. The elements 2 and 3 are vulcanized together in any well known manner and prior to the vulcanizing process, a scraping plate or blade 4 is positioned between the elements 2 and 3 and projects beyond one of the ends thereof and is provided with spaced openings 5 to permit the rubber of the elements 2 and 3 to pass therethrough when vulcanizing the elements 2 and 3 together for the purpose of firmly securing the blade or plate 4 to the cleaning elements 2 and 3. The blade or 60 plate has the free edge thereof beveled to form a scraping edge 6 whereby a person may easily remove hardened foreign matter from a surface prior to scouring the surface with either of the cleaning elements 2 or 3. 65

From the foregoing description taken in connection with the accompanying drawings, it will be noted that we have provided a very efficient cleaning device which can be manufactured and sold at a comparatively low cost 80 and will permit a person to scour surfaces of different textures without injury to the finish of the surfaces and also permit a person to easily remove foreign matter of a coarse or hardened nature from a surface 85 prior to scouring such surface with either of the cleaning elements.

While we have shown and described the preferred embodiment of our invention, it will be understood that minor changes in 90 construction, combination and arrangement of parts may be made without departing from the spirit and scope of the invention as claimed.

Having thus described our invention what 95 we claim is:

A cleaning device comprising a pair of cleaning elements one positioned upon the other and both tapering toward one of their ends and curved at their opposite ends to 100

5 permit said elements to be gripped firmly by a person with sufficient portions thereof exposed for rubbing over a surface to be cleaned, and a plate secured between the cleaning elements and projecting slightly beyond the first named ends of the cleaning elements for permitting the surface to be scraped thereby, and said plate having spaced openings to permit portions of the cleaning elements to extend therethrough when the latter are secured together.

10 In testimony whereof we affix our signatures.
